DESIGN.

F. MANKEY.

PANEL.

No. 17,185.

Patented Mar. 15, 1887.

UNITED STATES PATENT OFFICE.

FREDERICK MANKEY, OF WILLIAMSPORT, PENNSYLVANIA.

DESIGN FOR A PANEL.

SPECIFICATION forming part of Design No. 17,185, dated March 15, 1887.

Application filed December 30, 1886. Serial No. 223,058. Term of patent 7 years.

To all whom it may concern:

Be it known that I, FREDERICK MANKEY, of Williamsport, Lycoming county, Pennsylvania, have invented and produced a new and original Design for Panels, of which the following is a specification, reference being had to the accompanying photograph, forming part hereof.

My design consists in the elevated flat-surfaced parallelogram A, having curved or rounded edges. Parallel to and at each side of said parallelogram A are narrower parallelograms B C D E, also having rounded upper surfaces. The parallelograms C D are shorter than the parallelograms B E. At each corner of the design are the square elevations F, having rounded upper surfaces. Between the parallelograms are channels H G and I J. Upon the rounded upper surfaces of the par-

allelograms C D appears a different grain- 20 marking from that which appears upon the parallelograms A E B.

I claim—

The design for a panel, substantially as herein shown and described, which consists in the 25 raised flat-surfaced parallelogram A, having rounded edges, the raised parallelograms B C D E, and the square elevations F, having rounded surfaces, and the intermediate channels, G H I J, the parallelograms C D showing on their upper surfaces a different grain- 30 marking from that which appears on the parallelograms A E B.

FREDERICK MANKEY.
